UNITED STATES PATENT OFFICE.

FREDERICK WEEGMANN, OF SAN FRANCISCO, CALIFORNIA, ASSIGNOR TO THE CALIFORNIA PRE-PAYMENT METER COMPANY, OF SAME PLACE.

PREPAYMENT-METER.

SPECIFICATION forming part of Letters Patent No. 655,842, dated August 14, 1900.

Application filed March 20, 1899. Serial No. 709,833. (No model.)

To all whom it may concern:

Be it known that I, FREDERICK WEEGMANN, a citizen of the United States, residing at San Francisco, in the county of San Francisco and State of California, have invented certain new and useful Improvements in Prepayment-Meters, of which the following is a specification.

My invention relates to prepayment gas-meters in which the dropping of a coin and the manipulation of a coin-controlled apparatus render the gas-pressure available in the meter, while by a reciprocal action of the gas its pressure is rendered unavailable after the prepaid supply has been furnished.

15 The object of my invention is to provide means for locking the diaphragm or diaphragms of a meter and for automatically unlocking it or them, and I desire to distinguish my invention from those in which the action 20 of the coin apparatus opens a valve which is afterward closed by the reciprocal action of the gas-pressure. I do not apply a coin-controlled apparatus to the gas-valve, but to the diaphragms of a meter in order to lock such 25 diaphragms normally, to unlock them by manipulation of the coin mechanism, so that the gas-pressure can operate, and to relock them automatically at the end of the reciprocal action of the gas-pressure during which 30 the prepaid amount of gas has been supplied. My invention does not therefore affect the gas-inlet valve, which indeed may be open and admitting gas, although without producing any effect upon the meter-register, since 35 the primary operating means are normally locked.

As a matter of convenience in illustration and description I have shown my invention as applied to meters of a type having a single 40 diaphragm; but I can apply it to meters of other types with a plurality of diaphragms, the essential feature of my invention being to lock such diaphragms and not to operate a valve.

45 I have in the following specification described and in the accompanying drawings have illustrated a meter of the type referred to, which in itself forms no part of my invention and to which I lay no claim. I have also 50 described and shown a particular kind of

coin-controlled mechanism; but I can use other coin apparatus.

In the drawings, Figure 1 is an elevation of a meter of the kind specially referred to provided with a casing for supporting and containing the coin mechanism, such casing being partly broken away. Fig. 2 is a bottom plan of the same with both the meter and the said casing partly broken away. Fig. 3 is an end elevation looking toward the right side 55 of Fig. 1 and also broken away. Fig. 4 is a broken top plan. Fig. 5 is a detail view of the sliding rack controlled by the coin mechanism and the lock-actuating device operated thereby. Fig. 6 is a detail section of the 60 screw-shaft bearing.

A and A' represent the two parts of the meter, which are convex plates secured together at meeting flanges by bolts or screws 65. Such plates are preferably of circular 70 form, and in the chamber formed by them when united is clamped the yielding diaphragm B, which divides said chamber into two compartments, to which the gas is alternately admitted and from which alternately 75 it escapes. Formed with the meter-plates are the valve-chambers C C, each closed by a cap D. This structure is in communication with the gas-pipe E through openings in the caps D, the gas entering the meter at one side and 80 escaping through the other. In each valve-chamber is a partition 2, having ports 3 4, which are alternately opened and closed by the valves 5 and 6. The valves at one end are connected to corresponding valves at the other 85 end by valve-rods 7 and 8, and both valves at each end are connected together by a pivoted link 9. Thus the valve system is operated as a whole by motion communicated to one of the valve-rods. The means for operating the 90 valve-rods are best illustrated in Figs. 3 and 4, and I have shown them fully in order to illustrate completely the relation of the coin-actuated device with a meter of this type. It must be understood, however, that the general construction of the meter and the means for operating its system of valves form no part 95 of my invention excepting in combination with a coin-actuated mechanism applied thereto. A sliding bar F is attached to the diaphragm, 100

which extends at right angles thereto into a casing G, secured to the meter and which moves freely when impelled by the diaphragm between guide-rollers 10. To this bar are secured 5 oppositely-placed springs 11 and 12, whose free ends are connected to the bar 13, which slides at right angles to bar F between guide-rollers 14. A lever 15 connects the bar 13 to the valve-rod 7. The bar 13 is normally stopped 10 by the bar F during the motion of the latter; but at each end of such motion a slot f in bar F permits the bearing-shoulder of bar 13 to pass. At each extreme of motion one of the springs is under compression, and hence forces 15 the bar 13 through the slot and communicates motion to valve-rod 7 and to all the valves.

When gas is admitted to one side of the diaphragm, as by the valve 5, Fig. 2, the diaphragm is forced in one direction until the 20 valve-actuating devices just described operate, closing the valve 5 and opening valve 6. The gas then enters on the other side of the diaphragm and impels it in the opposite direction, the motion of the diaphragm back 25 and forth being continuous so long as the gas is entering the meter.

The consumption of gas is registered by any suitable dial-train connected to indicating-dials visible on the outside of the case, as 30 shown in Fig. 1. This mechanism is not shown in detail, as it forms no part of my invention; but I have illustrated fully the connections which make it operative, because such connections have an important relation 35 to the coin-actuated mechanism.

By reference to Figs. 1 and 3 it will be seen that a shaft H, which operates the register, is provided with a ratchet-wheel 16. A double pawl 17 engages opposite sides of the 40 ratchet, which is actuated by a bell-crank 18. One arm of this bell-crank is tubular to receive a rod 19, connected to the slide-bar F. The rod 19, fitting easily in the tube, communicates motion derived from the bar F to 45 the bell-crank, and so to the ratchet and register-train, and this result is produced at both movements of the bar F.

In applying coin-controlled mechanism according to my present invention the gas- 50 valves are not directly affected; but it is my purpose to unlock and automatically lock the mechanism which derives motion from the meter diaphragm or diaphragms and not to cut off the gas from the meter.

I do not wish to limit myself to any particular form or construction of coin-controlled 55 mechanism, but I prefer to use and have illustrated to a sufficient extent the device shown in Letters Patent granted to the California 60 Pre-Payment Meter Company, as assignee of Anselm C. Hammond, Jr., and myself, November 15, 1898, and numbered 614,103. Figs. 1 and 2 illustrate the external features 65 of this device, and the same figures in connection with Figs. 3 and 5 show the essential parts of its internal construction. I represents the outer casing of the coin mechanism,

J the operating-handle, and 20 the external coin-slot.

Without describing in detail the operation 70 of the coin device, it is sufficient for present purposes to say that when a coin of proper denomination has been supplied and the handle J turned motion is communicated to the ratchet 21 and gears 22 23, Figs. 2 and 3. 75 By "coin-controlled mechanism" it will be understood that I include only the mechanism located in the casing I, the operating-handle J, and the gear 22 rotated thereby. The gear 23 is fixed on the screw-shaft K, bearings for 80 it being formed in a supporting-bracket 24. Engaging with the screw K is a cross-head L, movable in both directions by the screw and guided by the rods 25. The relation of the 85 coin mechanism controlled by the handle J to the screw-shaft and intermediate gearing is such that the turning of the handle as far as it will go in one direction will move the cross-head L a certain distance upon its guides, and this distance bears a definite relation to the amount of gas paid for and is indicated by a pointer M, attached to the 90 cross-head and indicating on a visible scale on the edge of a slot 26, through which such pointer projects, Fig. 2. On the cross-head 95 and opposite this pointer is a projection 27, engaging with a rack 28, the rack working in a guide 29 (compare Figs. 2 and 5) and having the same motion as the cross-head. With this rack engages at proper times a partial 100 gear 30, having a lever 31, to which is pivoted a rod 32, which extends into that part of the casing which contains the bar F, operated by the meter-diaphragm. The rod 32 has a loose connection with a weighted bell-crank N, one 105 arm of which is a bolt 33, which enters a hole in the bar F and locks it, as shown in Fig. 1, thus locking the diaphragm.

In the drawings the device is shown in normal locked position, and it cannot be unlocked until the coin mechanism is properly operated. Supposing a coin to have been dropped and the handle J turned, the cross-head L is moved to the right in Figs. 1 and 2 and the rack 28 to the right in Fig. 5. The 110 rack being at this time engaged with the partial gear 30 turns the latter sufficiently to withdraw the bolt 33 from the bar F, thus 115 freeing the meter mechanism, which commences to operate. The bolt 33 is held out 120 because the disengaged tooth of partial gear 30 is now riding on the plain face of rack 28. The meter mechanism now commences to operate the screw-shaft K in the opposite direction, and thus to gradually restore the 125 cross-head to its normal position, which is attained when the prepaid amount of gas has been supplied. This is accomplished by gearing interposed between the screw-shaft and the register-shaft H, Fig. 1. On the end of 130 the shaft H is a worm 34, which engages with a pinion 35 on a counter-shaft 36. A similar worm 37 on shaft 36 meshes with a pinion 38 on the screw-shaft K and turns the latter in

a direction opposite to that derived from the coin mechanism. The cross-head and the rack 28 commence to move slowly back toward normal position or zero-point on the scale until the toothed part of the rack-bar engages the partial gear. This throws up the rod 32 and causes the bolt 33 to engage with the bar F as the hole in the latter registers with such bolt. The weighted bell-crank assembly 10 in maintaining the lock. The meter is now set and locked with the coin-scale at zero, and although gas may enter at one side of the diaphragm it cannot escape nor can the diaphragm be operated.

15 In Fig. 6 is shown a detail of the end of the screw-shaft K and a frictional connection between it and the pinion 38. The shaft has a bearing in a sleeve 39, and between such sleeve and shaft are frictional contact-surfaces 40 41. The sleeve is journaled in the bracket 24 and is held in place by a screw 42. The pinion 38 is fixed on sleeve 39. Since pinion 38 engages with a worm-gear, the friction is powerless when the coin device is actuated; but in the opposite direction the screw-shaft will be turned through the frictional contact.

As I have before intimated, I do not limit myself to a coin apparatus in combination 30 with the particular meter shown, which I have illustrated as typical of one kind of meter to which my invention is applicable. Nor do I limit myself to the particular coin mechanism shown, although I prefer to use 35 it. Neither do I limit myself to exact details of construction and arrangement described and shown, as I desire to avail myself of such modifications and equivalents as fall properly within the spirit of my invention.

40 Having thus described my invention, what I claim as new, and desire to secure by Letters Patent, is—

1. The combination with a meter having a diaphragm operated by gas-pressure, of a bar 45 connected to said diaphragm and adapted to be reciprocated as said diaphragm vibrates, gas inlet and outlet valves, means interposed between the same and said bar and controlled by the latter for operating said valves, means 50 for locking and releasing said bar, and coin-controlled mechanism for controlling the latter, substantially as described.

2. In combination with a gas-meter having a diaphragm, of a bar connected to said diaphragm, gas inlet and outlet valves controlled 55 by the movement of said rod, a locking-bolt adapted to engage said bar, coin-controlled

mechanism and means interposed between said mechanism and said bolt for operating the latter, substantially as described. 60

3. In combination with a gas-meter having a diaphragm, of a bar connected to said diaphragm, gas inlet and outlet valves controlled by the movement of said rod, a locking-bolt adapted to engage said bar, coin-controlled 65 mechanism, a screw-shaft adapted to be operated from the coin-controlled mechanism, a cross-head operated by said screw and means operated by said cross-head for controlling said bolt, substantially as described. 70

4. In combination with a gas-meter, having a diaphragm, of a bar connected to said diaphragm, gas inlet and outlet valves controlled by the movement of said rod, a locking-bolt adapted to engage said bar, coin-controlled 75 mechanism, a screw-shaft, a cross-head, a rack adapted to be shifted thereby, a gear meshing with said rack and a connection between said gear and said locking-bolt, substantially as described. 80

5. In combination in a gas-meter having a diaphragm, of gas inlet and outlet valves, a bar secured to said diaphragm, means interposed between the same and said valves for operating the latter, a locking-bolt for said 85 bar, coin-controlled mechanism, means operated therefrom for releasing said locking-bolt, a register-shaft operated from said bar, and connections interposed between said shaft and the releasing means for the locking-bolt for reengaging the latter. 90

6. In combination in a gas-meter having a diaphragm, gas inlet and outlet valves, a bar secured to said diaphragm, means interposed between the same and said valves for operating the latter, coin-controlled mechanism, a locking-bolt for said bar, a screw-shaft rotated from the coin-controlled mechanism in one direction, means interposed between the screw and the locking-bolt for controlling the 100 latter, a register-shaft, means operated from said bar for rotating the same, and gearing interposed between said register-shaft and said screw for rotating the latter in an opposite direction to the direction in which it 105 is rotated by the coin-controlled mechanism, substantially as described.

In testimony whereof I have affixed my signature, in presence of two witnesses, this 10th day of March, 1899.

FREDERICK WEEGMANN.
